J. W. LOY

ROTARY DISK DRILL

Filed Sept. 4, 1923

INVENTOR.
James W. Loy.

BY Dr. W. G. T. Gubberg
HIS ATTORNEY.

UNITED STATES PATENT OFFICE.

JAMES W. LOY, OF LONG BEACH, CALIFORNIA, ASSIGNOR OF ONE-HALF TO F. M. FISHBACK, OF LONG BEACH, CALIFORNIA.

ROTARY DISK DRILL.

Application filed September 4, 1923. Serial No. 660,922.

My invention relates to rotary disk drills, and has among its salient objects to provide a rotary disk drill having three rotary disks, set at angles to each other, and mounted to move about the longitudinal axis of the drill shank in which said rotary disks are mounted, as said drill shank is rotated, said rotary disks being so disposed that their bodily movement in operation causes them to 10 rotate about their own axes; to provide an improved type or form of rotary disks, each having two cutting edges; to provide improved axles or bearing pins upon which said rotary disks are mounted; to provide improved boxings or bearing sleeves for said rotary disks; and, in general, to provide an improved, practical and more efficient rotary disk drill for deep well drilling.

In order to fully explain my invention, 20 I have illustrated one practical embodiment thereof on the accompanying sheet of drawings, in which,—

Figure 1 is a side elevation of a rotary disk drill embodying my invention;

Figure 2 is a bottom plan view thereof;

Figure 3 is an enlarged side view of the lower end of one of the legs and a disk;

Figure 4 is a sectional view thereof taken on line 4—4, of Fig. 3; and Figures 5, 6 30 and 7 are sectional views, respectively, on lines 5—5, 6—6 and 7—7, of Fig. 4.

Referring more in detail to the drawings, 1 designates a drill head or shank having a tapered threaded upper end for connection 35 with a drill line for turning the same, and at its lower end said shank is shown formed with three extensions, 3, 3, each of which extensions is formed at its lower end with spaced legs, as 3^a, 3^a, substantially as illustrated. Between the legs, 3^a, 3^a, of each extension 3, is mounted a cutting disk 4, each disk having two cutting edges, as 4^a, 4^a, of substantially the form shown. A boxing or bearing sleeve 5, with angular sides, is fitted 40 into said disk in the manner indicated in Fig. 5, and is slightly longer than the diameter of said disk, as will be seen in Fig. 4, whereby said disk is free to rotate with little or no friction on the inside faces of the 45 legs 3^a, 3^a. A bearing pin 6, is inserted through the legs 3^a, 3^a, and the disk 4, therebetween, said bearing pin 6, having a head 6^a, at one end, and being slightly reduced in diameter, as at 6^b, within the bearing sleeve 50 or boxing 5, of the disk 4, and at its other

end it is shown to be further reduced in diameter, as at 6^c, and is internally threaded to receive a screw plug, 7, the head of which bears against the outer side of the leg 3^a, substantially in the manner shown in Figs. 60 3 and 4. Said leg 3^a, in its opening which receives the end, 6^c, of said bearing pin, 6, is provided with a transverse channel, as 3^b, opening inwardly, as indicated in Fig. 4, 65 said channel 3^b being wider for a part of its length, as at 3^c, and forming a sort of bayonet slot to receive a lug, 6^d, formed on the end 6^c of said bearing pin 6, and at one side thereof, whereby as bearing pin is inserted through said leg 3^a, its lug, 6^d, moves 70 through said channel, 3^b, until said bearing pin is fully in place, and then said pin is turned to move said lug 6^d, into the wider portion of said channel, 3^b, which forms a seat to receive the same. A separate piece 75 8 is then inserted into the end of said channel 3^b, at the side of said lugs 6^d, to prevent said pin from turning, as in Fig. 7. When the screw plug 7 is screwed into the end of said bearing pin, as in Fig. 4, said parts are 80 locked in place. In order to lock the screw plug 7 in place, a lock screw 9 is screwed into the side of the leg 3^a with its head in interlocking engagement with the head of the screw plug 7.

Thus I have provided an improved rotary disk drill having therein a plurality of rotary cutters standing in planes at angles to each other and at angles to the radial, whereby as said drill is rotated in operation, said disks are caused to rotate about their own axes. It is to be noted that no two disks stand parallel to each other, or in planes parallel to each other, but stand at angles to each other and also at angles to the radial. One of the difficulties often encountered in drilling operations is that the drill strikes a cavity or open crack and drops into it and under the force of rotation the drill is broken or the drill casing is 90 twisted off. By providing a drill head with three drill disks at angles to each other and also at angles to the radial, there is little chance for the drill to drop into a crack because the other disks are angles and will 95 support the whole. I have also provided a device with two cutting edges, axially spaced apart and while I have shown them as integral, it will be obvious that two disks might be mounted together with the same result, 100 105 110

that is, with two concentric cutting edges, axially spaced apart and following each other. This also reduces to a minimum the chance of a disk dropping into a crack.

5 I do not limit my invention to the details here shown for illustrative purposes, realizing that changes can be made in the same within the spirit of the invention, except as I may be limited by the hereto appended 10 claims.

I claim:

1. A rotary disk drill including a drill shank having three leg portions each terminating in a pair of legs and three cutter

15 disks rotatably mounted therein to move bodily around the axis of said drill shank and each standing at an angle to the radial, whereby their bodily movement in operation causes each to revolve about its own axis, 20 each of said cutter disks having two cutting edges of substantially the same diameter.

2. A rotary disk drill including a drill shank having an open center longitudinally and three cutter disks rotatably mounted in 25 the lower end thereof and standing in planes at angles to each other and at angles to the radial, each of said disks having two integral cutting edges concentric with each other and spaced apart axially thereof and a bearing 30 axle for each supported at both ends at opposite sides of said disks.

3. A rotary disk drill comprising in combination, a drill shank, having three pairs of spaced legs, three rotary cutter disks 35 mounted therein and standing in planes at angles to the radial and at angles to each other, a bearing pin for each of said cutter disks supported at both ends and having a head at one end and a screw plug at its 40 other end. said screw plug having a head portion of larger diameter than the diameter of the end of said bearing pin, and means for locking said screw plug in place in the end of said bearing pin.

45 4. A rotary disk drill comprising, in combination, a drill shank having six legs arranged in pairs, cutter disks rotatably mounted between said legs and in planes standing at angles to each other and to the radial, a bearing sleeve in each of said disks and interlocked therewith and being slightly longer than the diameter of said disk, a bearing pin through each pair of legs and said bearing sleeve, said pin having a screw plug

screwed into one end thereof and a bayonet 55 slot connection at its end with one of said legs.

5. A rotary disk drill comprising in combination, a drill shank having three pairs of legs, cutter disks rotatably mounted between said pairs of legs, there being two concentric cutting edges axially spaced apart between each pair of legs, each cutting edge having one straight side and one tapering side, said cutting edges following each other, 60 a bearing pin for each pair of legs and said cutter disks, and means for locking said bearing pin in place.

6. In a rotary disk drill, a pair of legs, a rotary cutter disk between said legs having 70 two concentric cutting edges axially spaced apart and turning about the same axis, each cutting edge having one straight side and one tapering side whereby to provide a sharp cutting corner edge as the advancing part 75 of the disk and a bearing pin through said legs and said cutter disk, said bearing pin having a screw plug with flanged head for securing it in place in said legs.

7. In a rotary disk drill, in combination, 80 a drill shank having three longitudinal extensions spaced apart, each of said extensions terminating in a pair of spaced legs, a rotary disk drill bit mounted between each pair of legs and the bits standing in planes 85 at angles to each other and at angles to the radial, whereby bodily movement with the drill shank causes each drill bit to rotate about its own axis, and a bearing pin for each pair of legs and each drill bit, with 90 a bearing sleeve in each drill bit on said bearing pin, and means for interlocking said bearing pin in place in said pair of legs, substantially as described.

8. In a rotary disk drill, a drill shank having spaced legs arranged in pairs around the center thereof, a rotary cutter having two cutter elements mounted between the legs of each pair in planes at angles to the radial of said shank in concentric relation 100 with each other and spaced apart axially to follow each other, a bearing pin for said rotary cutter elements, and means interlocking said bearing pin with said drill shank.

Signed at Los Angeles, Los Angeles 105 County, California, this 24th day of August, 1923.

JAMES W. LOY.
